E. HAUPT.
WASHLINE HANGER.
APPLICATION FILED OCT. 1, 1912.

1,074,321.

Patented Sept. 30, 1913.

UNITED STATES PATENT OFFICE.

ERNST HAUPT, OF PERTH AMBOY, NEW JERSEY.

WASHLINE-HANGER.

1,074,321.

Specification of Letters Patent. Patented Sept. 30, 1913.

Application filed October 1, 1912. Serial No. 723,332.

To all whom it may concern:

Be it known that I, ERNST HAUPT, a subject of the German Emperor, residing at Perth Amboy, in the county of Middlesex and State of New Jersey, have invented certain new and useful Improvements in Washline-Hangers, of which the following is a specification.

The present invention relates to washline hangers and has for its object to provide a device whereby the hanging of clothes for drying from the inside of the room without bending through the window will be rendered possible.

Another object of my invention is to provide a simple construction for the purpose named so as to reduce the cost thereof and thus bring such device within the reach of the general public. And a further object of my invention is to provide such construction as will allow of the device being readily and quickly fixed to the window frame or adjacent thereto and when not in use to be easily and readily removed.

My invention will be more fully understood by reference to the accompanying drawing in which similar reference characters denote corresponding parts and in which—

Figure 1 is a side view of the device; Fig. 2 is a top plan view thereof with some parts shown in cross section along line 2—2 of Fig. 1; Fig. 3 is an enlarged side view of a detail of the device and Fig. 4 is a rear elevation of the attachment wholly removed from the wall, a part of the line supporting arm being broken away.

The device consists of a base plate *a* of suitable shape through the center of which a cylindrical pin *b* is passed, which has an extension *b'* projecting outwardly at the rear of the plate *a* and which is secured in position against rotation to a rib *c* arranged at a right angle to the plate *a*. Rotatively mounted on the said pin *b* is a disk *d* which is integral with a ratchet wheel *d'*. Pivoted to the inner face of the plate *a* and adapted to coöperate with the said wheel are pawls *d''* (Fig. 3), which by springs *e* are held constantly in contact with said wheel. By means of this ratchet wheel and the pawls the disk *d* when turned on its axis in one or the other direction can be locked in position. The unlocking of the disk *d* so as to allow of its being turned can be accomplished by wires *f* or the like attached to the

pawls *d''* and extending through slots provided in a box-shaped cover *g* suitably fixed to the plate *a* and inclosing the disk *d*, wheel *d'*, the pawls *d''* and springs *e* and suitably secured to the plate *a*.

The cover *g* has a circular opening *g'* through which projects forwardly a sleeve shaped extension *d''* of the disk *d*. The forward end of the pin *b* carries a nut or washer *b''* whereby the disk *d* is held in position on pin *b*. The hood or sleeve extension *d''* is formed integrally with a forwardly projecting sector shaped piece *d''* which is perpendicular to the base plate *a* and which on its circumference is formed with ratchet teeth *d''*. The bifurcated end of an arm *h* embraces and is rotatively secured to said sector by means of a pin *h'* passed through the center thereof. Secured to the arm *h* is a spring actuated pawl *h''* which is adapted to coöperate with the ratchet teeth *d''*. Owing to the pivotal connection of the arm *h* to the sector piece *d''* and owing to the said sector being capable of revolving around the pin *b*, the arm *h* is capable of two movements in planes located at right angles to one another. The free end *h''* of the arm *h* is L-shaped and hinged or otherwise pivoted therein is a bracket *i* carrying a line pulley *j*.

Fixed to the plate *a* or in the cover *g* thereof and perpendicularly above one another are forwardly projecting pins *k*, on which outside of the casing formed by the part *g* are mounted rollers or pulleys *l*, the object of which will be described in connection with the operation of the device.

The new device being designed to be movably attached to any one of the lateral bars of a window frame or to parts adjacent thereto, I provide the following means for its attachment: An L-shaped metal plate *m* is provided on both sides with substantially keyhole or T-shaped recesses *m'* and on one side with a central inwardly bent U-shaped portion *m''*. Below each of the T-shaped recesses and surrounding three sides of the narrow portions thereof is secured to the rear or outer surfaces of the plate *m* a U-shaped flange *m''*. This angle plate *m* is adapted to be fixed to any one of the side bars *W* of a window frame or wall, either from the outside or the inside of a room, in such a manner as to embrace said window frame or wall from two sides or around the corner. In so affixing the plate, there will

be left some free space m^5 between the sides of the frame or wall and those of the plate m , owing to the rearwardly projecting central part m^2 and the flanges m^3 . This space is designed to accommodate the rearwardly projecting ends of screw bolts o and nuts p whereby the base plate a is secured to the plate m .

After the engagement of the nuts between the **U**-shaped flanges the bolts can be turned to tighten the nuts. The bend m^2 will extend over the part b' when the plate m is placed against the rear of the base a and the rib c . Of course, the part b' can be omitted and the spindle b otherwise fixed to the rib c . In that case, the bend m^2 can be omitted. In the example shown, when the plate m is arranged on the side of the frame opposite to that indicated in Fig. 2, the recesses m' will extend in reverse direction to that shown in Fig. 4. In that case before the nuts are tightened the base a will have to move upwardly instead of downwardly.

After first ascertaining to which side of the window frame it is most convenient to fix the plate m , in order that the line q may be conveyed around the line pulley carried by the pole (not shown) in the yard, the plate m is fixed in position (see Fig. 2). The device is then secured to the plate m by slipping its screw bolts o and nuts p through the enlarged portions of the **T**-shaped recesses m' of the plate m and then by depressing the base a , thus causing said bolts o to engage the reduced portions of the **T**-shaped recesses and the square nuts p to be lodged between the **U**-shaped flanges m^3 . Through the rear rib c of plate a screw bolts o' and nuts p' also engage the **T**-shaped recesses and by the depression of the plate a , in a similar manner as bolts o and nuts p are caused to engage the reduced portion of the **T**-shaped recesses m' and the **U**-shaped flanges m^3 respectively. The device thus becomes locked in position of use. The arm h in non-operative position occupies a vertical position (see dotted lines in Fig. 1) projecting downwardly, and the endless line q which runs over the pole pulley (not shown) is carried around the pulley j and around the upper pulley l .

When the clothes are to be hung on the line, the arm h must be first swung into horizontal position (see full lines in Fig. 1) extending inwardly into the room. As the arm is locked in its downward position by the pawls d^6 engaging the teeth of the

wheel or disk d , the same must be first unlocked which is effected by pulling on the wires f . After the arm h is brought into horizontal position it again becomes locked therein by the engagement with the wheel d of the pawls d^6 when released. The lower part of the line q now is in position to receive the clothes r and the line can be fed from within the room outwardly. The pulley j , owing to the pivotal connection of its bracket i to arm h adjusts itself according to the location of the pole pulley.

If the location of the pole pulley requires a slanting position of the arm relative to the window frame, the said arm can be swung around its horizontal pivot h' toward or into the dotted position shown in Fig. 2. This can be effected only after the lifting of pawl h^2 by means of its grasp h^4 from the toothed sector d^3 . After such adjustment and on release of the pawl h^2 the latter, owing to the spring h^5 actuating it, returns into engagement with sector d^3 and locks the arm in the new position.

When the clothes are all hung and fed outwardly the lower part of the line carrying the clothes may be lifted onto the upper pulley l , to thereby stretch the line more taut, and then the arm h may be swung back into its vertical position (see dotted lines in Fig. 2) to be out of the way.

I do not wish to limit myself to the details of construction shown and described, as various modifications may be made therein without deviating from the principle of my invention.

What I claim and desire to secure by Letters Patent is:

In combination with a wash line hanger comprising a perforated base, of an **L**-shaped plate having in both wings or sides **T**-shaped recesses and flanges around the reduced portions of said recesses and being adapted to be fixed around a corner of a stationary part, and bolts carrying square nuts and adapted to be passed through said perforated base and to engage with the nuts the recesses in said plate, said nuts after depression of said base being adapted to engage between said flanges and to be held against rotation.

In testimony whereof I affix my signature in presence of two witnesses.

ERNST HAUPT.
